DISPOSABLE FILTER

James P. Whelan, Union St., Pembroke, Mass. 02359

Filed Jan. 20, 1966, Ser. No. 699

Term of patent 14 years

(Cl. D44—29)

FIG. 1

FIG. 1 is a top plan view of a disposable filter showing my new design, the broken lines indicating the extent of the fabric component partially shown in full lines, FIG. 2 is a front elevational view thereof, and FIG. 3 is a side elevational view.

The essential feature of the design resides in the combination of the sinuous division line, the particular form of cut out portions and the particular tab configurations.

I claim:

The ornamental design for a disposable filter, substantially as shown and described.
